DESIGN FOR A SUN HAT

Edward Wittcoff, University City, Mo.

Application October 13, 1933, Serial No. 49,475

Term of patent 3½ years

To all whom it may concern:

Be it known that I, EDWARD WITTCOFF, a citizen of the United States, residing at 7220 Pershing Avenue, University City, in the county of St. Louis, and State of Missouri, have invented a new, original, and ornamental Design for Sun Hats, of which the following is a specification, reference being had to the accompanying drawing, forming part thereof.

I claim:
The ornamental design for a sun hat, as shown.

EDWARD WITTCOFF.
